US0D1000953S

(12) **United States Design Patent** (10) Patent No.: **US D1,000,953 S**
(45) Date of Patent: ** Oct. 10, 2023

(54) **COMBINED TRIGGER SPRAYER AND SHROUD**

(71) Applicants: **Market Ready, Inc.**, Round Lake Park, IL (US); **Cupcake LLC**, New York, NY (US)

(72) Inventors: **Brandon Donnelly**, New York, NY (US); **Kyle Hansen**, Hartland, WI (US); **Alan Cormley**, Blessington (IE); **Milan-bob Patadlas**, Talisay (PH); **Michael Sawant**, Lake Forest, IL (US)

(73) Assignees: **Market Ready, Inc.**, Round Lake Park, IL (US); **Cupcake LLC**, New York, NY (US)

(**) Term: **15 Years**

(21) Appl. No.: **29/774,747**

(22) Filed: **Mar. 18, 2021**

(51) LOC (14) Cl. **09-07**

(52) U.S. Cl. **D9/448**
USPC ....

(57) **CLAIM**

We claim an ornamental design for combined trigger sprayer and shroud, as shown and described.

DESCRIPTION

FIG. 1 is a top, front, right perspective view of a combined trigger sprayer and shroud, showing in our new design; FIG. 2 is bottom, right, rear perspective view thereof; FIG. 3 is a front side elevation view thereof; FIG. 4 is a rear side elevation view thereof; FIG. 5 is a left side elevation view thereof; FIG. 6 is a right side elevation view thereof; FIG. 7 is a top view thereof; FIG. 8 is a bottom view thereof; FIG. 9 is a top, front, right perspective view of the shroud component, shown independently to show aspects of the design not visible when combined; FIG. 10 is bottom, right, rear perspective view thereof; FIG. 11 is a front side elevation thereof; FIG. 12 is a rear side elevation view thereof; FIG. 13 is a right side elevation view thereof; FIG. 14 is a left side elevation view thereof; FIG. 15 is a top view thereof; FIG. 16 is a bottom view thereof; FIG. 17 is a top, front, right perspective view of a trigger component, shown independently to show aspects of the design not visible when combined; FIG. 18 is a bottom, right, rear perspective view thereof; FIG. 19 is a front side elevation view thereof; FIG. 20 is a rear side elevation view thereof; FIG. 21 is a right side elevation view thereof; FIG. 22 is a left side elevation view thereof; FIG. 23 is a top view thereof; and, FIG. 24 is a bottom view thereof.

The broken lines are shown for the purpose of illustrating both parts of the article as well as environmental subject matter. None of the broken lines form part of the claimed design.
